(57) **CLAIM**

The ornamental design for a single lead electrocardiograph detector as shown and described.

DESCRIPTION

The patent or application file contains at least one drawing executed in color. Copies of this patent or patent application publication with color drawing(s) will be provided by the Office upon request and payment of the necessary fee.

1. Single lead electrocardiograph detector

1.1 : Perspective

1.2 : Front

1.3 : Back

1.4 : Left

1.5 : Right

1.6 : Top

1.7 : Bottom

The product is used for sticking to the body surface and collecting human electrocardiograph signals.
